UNITED STATES PATENT OFFICE.

WILHELM MAUSS, OF JOHANNESBURG, TRANSVAAL, SOUTH AFRICA.

PERCUSSIVE ENGINE.

1,309,649.

Specification of Letters Patent. Patented July 15, 1919.

Application filed November 6, 1915. Serial No. 59,982.

To all whom it may concern:

Be it known that I, WILHELM MAUSS, a British subject, and a resident of Commercial Exchange Buildings, Johannesburg, 5 Transvaal Province, Union of South Africa, have invented certain new and useful Improvements in Percussive Engines, of which the following is a specification.

The present invention relates to fluid actuated rock drills channeling machines and 10 coal cutters which are designed for rapid and continuous reciprocation of a free piston which is propelled without material retardation throughout its full normal stroke, 15 and in which the distribution of working fluid is effected by a valve which is controlled solely by the working piston and so as to be thrown according to the position of the latter relatively to the cylinder.

20 The period of the cycle of such a machine may be shortened and the number of blows per minute consequently increased by causing the piston on approaching the rearward end of its stroke to compress a body of the 25 working fluid which is to be used for effecting the next forward stroke and which is already present in the rear cylinder chamber at working pressure; said body being of substantial extent but limited to that contained in the rear cylinder chamber with or 30 without the air passage connected thereto. Since however there is always loss by leakage and absorption of heat by the cylinder walls, the fluid so compressed tends on re- 35 expansion to fall below the pressure from which it was initially compressed and so reduce the force available to propel the piston on its forward stroke.

To overcome this drawback the present 40 invention provides in a machine as specified a non-return valve governing a fluid supply port which leads to and is constantly in communication with the rear cylinder chamber, said non-return valve being arranged to 45 be closed by displacement of fluid from the rear cylinder chamber and being free at all times to open to pass fluid to said chamber when the pressure of the fluid on its supply side is not less than that of the fluid on its 50 cylinder side. By the rear cylinder chamber is meant the chamber in which the rear working pressure face of the piston works and in which is contained the fluid which acts upon said pressure face to drive the 55 piston on its blow stroke.

In the accompanying drawings,

Figure I shows an engine having continu-

ous pressure on its rear piston face, and embodying one arrangement of the invention.

Fig. II is a similar view to Fig. I, but 60 with the parts in a different position.

Figs. III and IV show the same type of engine with the invention differently embodied.

Fig. V is a partial section plane taken on 65 the line X—X of Fig. I.

Referring to Figs. I and II the cylinder comprises a large front chamber 1 and a smaller rear chamber 2. The piston correspondingly has a relatively large front member 3 and a smaller rear member 4, providing respectively the forward pressure area 70 5 and the rear pressure area 6.

The distributing valve 7 works in the valve chamber 8. It governs admission to 75 and exhaust from the front cylinder chamber 1 and is arranged closely contiguous thereto. 9 is an inlet port and 10 an exhaust port. 11 is a port from the valve chamber 8 to the front cylinder 1. During 80 its reciprocation the valve alternately connects the cylinder port 11 to one or other of the ports 9 or 10.

Any suitable provision is made for actuating the valve 7. As shown, a passage 12 85 is carried from the front end of the valve chamber to the forward piston chamber 1 and a passage 13 from the rear of the valve chamber to the rear piston chamber 2. During the rearward movement of the piston, 90 the rear end of the valve chamber is exhausted through the passage 13, the annular recess 14 around the piston, and the hole 15 in the cylinder wall. Working fluid herein called air is admitted to the front end of the 95 valve chamber from the front cylinder chamber through the passage 12, and the valve is consequently thrown backward as shown in Fig. II. Before the blow is struck the passage 12 is connected to atmosphere 100 by the recess 14 and the hole 15; while air passes into the passage 13 and the valve is thrown forward again as in Fig. I.

Air is supplied to the rear cylinder chamber by the port 16, one end of which is in 105 permanent communication with the live air supply and the other end of which opens into said chamber some distance from the rear end of the cylinder. From said port a branch 17 extends to the extreme rear end 110 of the cylinder. In said branch is fitted the non-return valve 18 which opens toward the cylinder.

In Fig. I the piston is shown as though it

has just struck its blow. Live air is now acting on both piston faces 6 and 5 and the latter being of greater area the piston is forced back. During the first part of such 5 backward movement air displaced from the cylinder 2 assists in feeding the front cylinder 1 rapidly and completely. The piston area 5 is considerably larger than the area 6 and the admission of full pressure air to 10 the former is continued through the greater part of the rearward stroke so that the piston accelerates at a high rate during the greater part of said stroke.

When the piston has moved back a certain 15 distance as indicated by the full lines of Fig. II the valve 7 is thrown over and the front cylinder 1 is exhausted. At about the same moment the piston head 4 closes the port 16. The piston, having acquired 20 considerable rearward momentum, continues to move backward to about the position indicated by the dotted lines Fig. II, thereby compressing the air inclosed in the cylinder chamber 2. Said air being initially at working 25 pressure is rapidly compressed to a high degree with the result that the piston is quickly stopped and restarted on the forward stroke with considerable momentum. When, during the reexpansion of the air, 30 the pressure in the chamber 2 drops to that of the air supply, the valve 18 opens and maintains full working pressure behind the piston, and the port 16 does the same when it is again uncovered by the piston.

In the arrangement shown in Fig. III the 35 non-return valve 18 itself controls the compression of the air. It is fitted in the main inlet 9 of the machine, beyond both the distributing valve 7 and the port 16 so that 40 the air going to either the valve 7 or the port 16 passes said valve 18. The latter extends to the rear end of the cylinder.

The method of operation is that while 45 the valve 7 is in its forward position, air is displaced from the rear cylinder 2 and passes into the front cylinder 1 together with further air from the inlet 9. Upon the valve 7 being thrown over to cut off the supply to the front cylinder, the air which 50 is being displaced from the rear cylinder tends to pass back into the inlet 9. This closes the valve 18 and causes the air in the rear cylinder chamber 2 and the port 16 to be compressed. During the ensuing forward 55 stroke the valve 18 re-opens and passes further air to the rear cylinder as soon as the pressure therein falls to that of the supply.

In the modification shown in Fig. IV the 60 non-return valve 18 is positioned in the port 16, which is not covered by the piston. The

result is that compression begins in the rear cylinder immediately on the return stroke. This reduces the back kick of the machine but tends to prolong the cycle, as compared 61 with the Fig. I construction.

The powerful reversal of the piston enables a much higher piston velocity than usual to be used during the rearward stroke. Surplus energy so expended is stored 70 by the compression and reexpansion of the air and returned to the forward stroke, thus enabling the cycle to be accelerated throughout. Speed is also gained by the suppression of the air wave which, in the absence of non-return valve 18, is sent back 75 through the supply pipe by the continued movement of the piston after early admission of air to the cylinder and results in a momentarily decreased pressure for the reversal of the piston.

I claim:

1. In a rock drill channeling machine or coal cutter, the combination with the cylinder and piston of passage means arranged 85 within said cylinder and adapted to maintain continued fluid pressure on the rear working piston area, a non-return valve in said passage means, and a distributing valve means adapted to supply working fluid 90 to the front cylinder chamber during the rearward stroke and thereafter immediately to exhaust said chamber.

2. In a rock drill channeling machine or coal cutter, the combination with the cylinder of a differential piston having its rear working pressure face smaller than its front working pressure face, passage means arranged within said cylinder and adapted to maintain continued fluid pressure on said 100 rear piston area, a non-return valve in said passage means, and a distributing valve means adapted to supply working fluid to the front cylinder chamber during the rearward stroke and thereafter immediately to 105 exhaust said chamber.

3. In a rock drill channeling machine or coal cutter, the combination with the cylinder and piston of passage means within said cylinder such passage extending into the 110 rear cylinder chamber beyond the rear limit of the piston's travel and arranged to maintain continued fluid pressure on the rear working piston area, a non-return valve in said passage means, and a distributing valve 115 means adapted to supply working fluid to the front cylinder chamber during the rearward stroke and thereafter immediately to exhaust said chamber.

In testimony whereof I affix my signature.

WILHELM MAUSS.
